DISCHARGER FOR CENTRIFUGAL MACHINES

Pieter van Riel, Delft, Netherlands, assignor to
N. V. Machinefabriek "Reineveld", Delft, Netherlands,
a company of the Netherlands

Application June 29, 1937, Serial No. 151,032.
Renewed February 14, 1939. In Germany July
2, 1936

4 Claims. (Cl. 233—22)

The invention relates to means for emptying the revolving drum of a centrifugal machine.

It has already been suggested to provide the drum of a centrifugal machine with means for removing the substantially solid material accumulated on the inner drum wall, said means consisting of a plurality of disks having a smooth circumferential cutting edge and assembled on a shaft mounted in substantially parallel relation 10 with the axis of the drum and adapted for movement towards and away from said inner wall.

In accordance with my present invention, said disks, at least part of them, are toothed or otherwise provided along their circumference with a 15 series of recurrent projections and recesses, and are freely revoluble relative to one another.

When the said disks are drawn into frictional engagement with the material which has been impinged against the inner wall of the revolving centrifugal drum, they are compelled to follow said rotary movement, so that the cylindrical body formed by the coaxial disks disintegrates the material and allows the particles thereof to be removed from the drum.

25 The drawing illustrates, by way of example only, an embodiment of my present invention. On this drawing:

Fig. 1 is a vertical axis sectional view of part of a horizontal centrifugal machine,

30 Fig. 2 is a fragmentary sectional view along the line II—II in Fig. 1,

Fig. 3 is a front view of a detached disk, drawn on an enlarged scale, and

35 Fig. 4 is a side elevational view of three disks, showing the relative positions they may assume during operation.

Mounted within the stationary housing 5 of the centrifugal machine is the revoluble drum or basket 6. Rotatably mounted in a bearing 7 of said housing 5 is the casing 8 of a screw conveyor 9, the axis of which is in parallel relation with the axis of the drum 6. The shaft of the screw conveyor 9 is designated by 10.

Secured to the casing 8 are two radial arms 45 8a, 8b supporting a shaft 11 mounted in parallel relation with shaft 10. Freely revoluble about shaft 11 are a plurality of disks 12a, 12b, 12c . . . of equal sizes, each disk being provided with a circumferential series of radial fingers 13 of very 50 hard material and of U-shaped cross-section. The cylindrical body formed by these disks extends through the full axial length of the drum 6. The disks 12 may be and preferably are provided with a bushing 11' on which the disks are 55 freely rotatable. The disks may be and prefer-

ably are separated by more or less resilient spacing elements 12', shown more particularly in Figure 4.

The casing 8 is adapted by mechanism not shown on the drawing to be oscillated through a 5 suitable angular distance in such a manner that the cylindrical body 12 composed of disks 12a, 12b, 12c . . . and associated therewith moves towards or away from the inner drum wall. The shaft 10 is coupled with a transmission not shown, 10 so that the screw conveyor can be driven at a suitable speed. The casing 8 is further provided with an axial slot 14 adapted to receive the stream of disintegrated material disengaged by the disks 12a, 12b, 12c . . . from the inner wall 15 of the drum.

If, owing to the normal function of the centrifugal machine, a substantially solid layer of sufficient thickness has accumulated on the inner wall of the fastly revolving drum 6, the feed 20 of the machine is cut off and the casing 8 turned, until the cylindrical body 12 contacts with said layer. The disks 12a, 12b . . . are thus compelled by frictional engagement to follow the 25 rotary movement of the drum, so that their fingers 13 act to disintegrate the material. The disintegrated material is thrown, tangentially relative to the cylinder 12, through the slot 14 into the casing 8, from which it is discharged by the screw conveyor 9. 30

Preferably, the outer ends of arms 8a, 12b are formed as hooks, scrapers or the like extending circumferentially of the cylinder 12, so that the solid material accumulated on the inner drum wall is also scraped off in the radial planes of 35 said arms, i. e. in the regions beyond the reach of the disks 12a, 12b . . .

The disks provided with recurrent projections and recesses along their circumference may alternate with disks of relatively soft material and 40 having a smooth circumference. As stated, the essential feature of my invention is that the cylindrical body 12 on shaft 11 is composed of disks that are freely revoluble relative to one another and that they are provided with a circumferential series of teeth or like projections 45 adapted to disintegrate the material when the disks are brought into frictional engagement with the layer of solid material accumulated on the inner drum wall. 50

Preferably, the axis of the cylindrical body 12 is mounted so as to make a very small angle with the axis of the drum.

It will be understood that my invention is 55 equally suitable for a centrifugal machine hav-

ing a perforated drum as for a centrifugal separator, the drum of which has an impervious wall. Moreover, it will be obvious to any one skilled in the art that the cylindrical body 12 may 5 also be mounted so as to be adapted for rectilinear reciprocatory movement, the only requirement to be fulfilled in this respect being that said body can be moved towards and away from the inner wall of the basket.

10 What I claim is:

1. In combination with a drum of a centrifugal machine, a cylindrical body mounted for rotation in the drum, the body being arranged at a point remote from and parallel with the axis of the drum, a shaft supported by and movable in the turning of the body toward and from the interior surface of the drum, and a series of disks mounted for free relative rotation on the 15

shaft, the series of disks being bodily movable into and out of contact with the interior surface of the drum by adjustment of the cylindrical body.

2. A construction as defined in claim 1, where- 5 in the peripheral surfaces of the disks are formed with spaced material removing projections.

3. A construction as defined in claim 1, where- 10 in the cylindrical body is formed with an opening facing the disks to receive part of the material removed by the disks, and means within the cylindrical body for compelling discharge movement of the received material.

4. A construction as defined in claim 1, where- 15 in the disks together provide an operative length substantially equal to the axial length of the drum.

PIETER VAN RIEL.
